DESIGN FOR A DISPLAY BOX OR SIMILAR ARTICLE

Morris Walhimer, New Haven, Conn.

Application December 30, 1944, Serial No. 117,164

Term of patent 3½ years

(Cl. D80—5)

To all whom it may concern:

Be it known that I, Morris Walhimer, a citizen of the United States, residing at New Haven, in the county of New Haven and State of Connecticut, have invented a new, original, and ornamental Design for a Display Box or Similar Article, of which the following is a specification, reference being had to the accompanying drawing, forming a part thereof.

In the drawing:

Fig. 1 is a front perspective view of a display box or similar article, showing my new design;

Fig. 2 is a similar perspective view with the cover removed;

Fig. 3 is a perspective view of the same, similar to Fig. 2, showing the display box or similar article fully opened; and

Fig. 4 is a rear perspective view of Fig. 1.

I claim:

The ornamental design for a display box or similar article, as shown.

MORRIS WALHIMER.
